DESIGN FOR A LAMP SHADE

Jean Kurzac, Philadelphia, Pa., assignor to Albe
Lamp & Shade Co., Philadelphia, Pa., a partner-
ship consisting of Albert E. Smith and Henry
Benedict

Continuation of application Serial No. D-81,323,
November 23, 1938. This application December
28, 1938, Serial No. 82,011.

Term of patent 3½ years

To all whom it may concern:

Be it known that I, Jean Kurzac, a citizen of the United States, residing at Philadelphia, in the county of Philadelphia and State of Pennsylvania, have invented a new, original, and ornamental Design for a Lamp Shade, of which the following is a specification, reference being had to the accompanying drawings, forming part thereof.

Fig. 1 is a perspective view of the lamp shade showing my new design;

Fig. 2 is a bottom plan view;

Fig. 3 is a top plan view; and

Fig. 4 is an enlarged fragmentary view.

The dominant feature of the design is the flounce shown in solid lines. The dot and dash lines indicate conventional features of the design. The dot and dash lines directly overlying the flounce represent a ribbon.

This application is a continuation of application Serial No. D-81,323 which I filed on November 23, 1938.

I claim:

The ornamental design for a lamp shade, substantially as shown and described.

JEAN KURZAC.
